ANDREW J. BROOKOVER, OF DOWNTONTOWN, PENNSYLVANIA

APPARATUS FOR SCREENING PAPER STOCK

Application filed October 3, 1928. Serial No. 309,957.

This invention relates to apparatus for screening paper stock and relates more particularly to the driving arrangement for the diaphragms of a series of screen boxes.

5 One object of the invention is the provision of a screen-box arrangement embodying a series of screen boxes, and each screen box having a number of flexible vibratory diaphragms which are so driven from a series of 10 shafts that each shaft operates a diaphragm of each screen box.

Another object of the invention is the provision of a series of screen boxes arranged in this manner, each screen box having a number 15 of flexible diaphragms arranged in the screen box transversely of the series of boxes, with the operating shafts for the diaphragms extending throughout the entire length of the series and operated by individual belt drives 20 or the like.

Other objects and advantages of the invention will be apparent from the following description and from the accompanying drawings, in which

25 Fig. 1 is a top plan view of a series of screen boxes embodying the present invention;

Fig. 2 is a side elevation of the series of screen boxes; and

30 Fig. 3 is a section on the line 3—3 of Fig. 1 through one of the screen boxes.

Referring more particularly to the drawings by reference numerals 10 indicates a screen box adapted for the screening of 35 paper-pulp stock and the like. This screen box embodies a number of screens 12 arranged below the top of a pulp-stock receiver 13 common to the various screens of the box. Below the screens are a series of flexible dia-

40 phragms 14 which are clamped at their edges by means of clamp boards 15 which thus divide the screen box into sections, each section including one or more flexible diaphragms. Each of the flexible diaphragms 45 is attached to a block 16 which is fixed at the top of a rod 17 the lower end of which is provided with an eccentric or cam follower operated by a shaft, such as the shaft 34. As shown, the screen box embodies five sections or diaphragms although of course more

or less diaphragms than this may be provided.

In the screening of paper-pulp stock the stock is supplied in a fluid state to the stock receiver 13 and the stock is sifted or screened by the screens 12, this screening action being assisted and induced by the vibratory diaphragms 14 which create a rapid movement of the material through the screen spaces and prevent the clogging of the screen. The 55 screened material flows out of a suitable outlet opening at one side of each of the sections of the screen box into a trough or receiver 20. Movement of the unscreened material which is placed in the stock receiver 60 13 is effected longitudinally of the screen box by the usual blade or paddle carried by a shaft 21 and driven in any suitable manner.

A number of screen boxes or machines, 70 similar to the box 10, are arranged in a series as shown in Figs. 1 and 2. In the screening of quantities of paper stock it is usually necessary to provide a number of different screening machines, all operating on the paper stock to screen sufficient material for 75 the paper-making machine. These screening machines as shown in Fig. 2 are preferably arranged at successively lower levels so that the unscreened material from the different boxes is collected in a common longitudinally extending fluid conductor, not 80 shown, and led to the last box in the series, termed a rescreening box and indicated 30. As shown in the drawings there are eight 85 screen boxes in the series, indicated 10, 24, 25, 26, 27, 28, 29 and 30, although of course this number may vary quite considerably dependent upon the total machine capacity desired.

It has heretofore been the practice to drive 90 the cams, knockers or eccentrics connected to the various flexible diaphragms with a shaft extending longitudinally of a screen box operating all the diaphragms on this individual screen, so that, should the power or 95 drive become ineffective on this one shaft this entire screen would be out of operation. Or where a number of screens are driven by one shaft with all the diaphragms of each screen operated by this one shaft, in case of 100

failure of the power at this one point all the screens will be out of operation. Should a mechanical part of the vibrating devices become effective and require the power to be taken off for repair then all the screens are rendered ineffective. In accordance with the present invention however the screen-box diaphragms are driven as follows:

Arranged longitudinally of the series of screen boxes are drive shafts 33, 34, 35, 36 and 37, these shafts extending the full length of the series, and each shaft being preferably centrally located below one of the flexible diaphragms of a screen box. Thus the shaft 15 33 extends below the end diaphragm of each of the various screen boxes in the series. Each shaft thus operates one of the flexible diaphragms of each of the various screen boxes so that in case any one of the shafts 20 is stationary, the practical operation of the series of machines is not interrupted, and none of the screen boxes overflows due to the fact that the other screens of the screen boxes are not affected and all continue in their 25 effective operation. As shown the shafts are made up of coupled sections.

The ends of the various shafts 33 to 37 preferably project beyond the ends of the series, and are independently driven by suitable means, such as the driving belts 38 30 which are operated in any suitable manner. As the various belts 38 are independent of one another the diaphragm-operating shafts are independently driven and a series slipping 35 of one of the belts on its driven belt pulley or the breaking or disconnection of a belt affects equally a diaphragm in each of the various screen boxes in the series. Furthermore where, as shown, the number of screen 40 boxes arranged in the series exceeds the number of diaphragms provided in each screen box fewer driving shafts need be employed, and the arrangement is such that the individual power drives for the various shafts 45 may be readily effected in a more desirable manner from power shafting usually available at one side of such a series of machines. As the shafting on the screens may run parallel to the usual constant drive shaft of the 50 paper machine, the necessity of greater twist belts or bevel gears is eliminated.

While the form of apparatus herein described constitutes a preferred embodiment of the invention, it is to be understood that 55 the invention is not limited to this precise form of apparatus, and that changes may be made therein without departing from the scope of the invention which is defined in the appended claims.

60 What is claimed is:

1. Apparatus for screening paper stock comprising a series of screen boxes, each box having a plurality of flexible diaphragms, screen means associated with said diaphragms and said boxes, a device for vibrat-

ing each diaphragm, and means for operating said devices comprising a series of shafts, each shaft arranged to extend across the series of boxes from one end to the other of the series, and means on each shaft for operating a device of each box.

2. Apparatus for screening paper stock comprising a series of screen boxes, each box having a plurality of flexible diaphragms arranged laterally of the series of boxes, screen means associated with said diaphragms in said boxes, a device for vibrating each diaphragm, and means for operating said devices comprising a series of shafts, each shaft being arranged below the entire series of boxes and in parallel arrangement with each other, and means on each shaft for operating a device of each box.

3. Apparatus for screening paper stock comprising a series of screen boxes, each box having several flexible diaphragms arranged laterally of the series of screen boxes, the number of screen boxes exceeding the number of flexible diaphragms in each box, screen means associated with said diaphragms and said boxes, a device for vibrating each diaphragm, and means for operating said devices comprising a series of shafts, each shaft arranged to extend below the series of boxes from one end to the other of the series and parallel with the other shafts, independent drive belts for each of said shafts, and means on each shaft for operating a device of each box.

In testimony whereof I hereto affix my 100 signature.

ANDREW J. BROOKOVER.

CERTIFICATE OF CORRECTION.

Patent No. 1,737,296.

Granted November 26, 1929, to

ANDREW J. BROOKOVER.

It is hereby certified that error appears in the printed specification of the above numbered patent requiring correction as follows: Page 2, line 4, for the word "effective" read "defective"; same page, line 34, for the word "series" read "serious"; and that the said Letters Patent should be read with these corrections therein that the same may conform to the record of the case in the Patent Office.

Signed and sealed this 31st day of December, A. D. 1929.

**M. J. Moore,
Acting Commissioner of Patents.**
